POWER BENDING APPARATUS

Chester L. Lewellen, Detroit, Mich., assignor to
Motor Products Corporation, Detroit, Mich., a
corporation of New York

Application July 24, 1933, Serial No. 682,024

10 Claims. (Cl. 153—46)

This invention relates generally to bending apparatus and refers more particularly to machines for forming a curvature in strip stock.

Although it will be apparent as this description proceeds that the machine forming the subject matter of this invention is capable of bending various types of strip stock, nevertheless, the apparatus selected for the purpose of illustration finds particular utility when employed in forming curvatures in garnish moldings of the type used extensively in the manufacture of vehicle bodies.

Due to the difficulties heretofore experienced in satisfactorily actuating the bending fixtures of machines of the general type previously set forth by power means, it has been customary in the past to operate these fixtures manually, notwithstanding the fact that this mode of operation not only materially limits production, but it requires considerable man power, especially in cases where the stock to be bent is of relatively heavy gauge.

The present invention provides a relatively simple solution for the problems heretofore encountered in applying power to bending fixtures of the type set forth, with the result that the man power heretofore considered essential in the operation of such apparatus is not only appreciably reduced, but the potential production of the same is materially increased with a consequent saving in cost of manufacture. In other words, it is the principal object of the present invention to render the operation of the bending fixture practically automatic, and the manner in which this is accomplished will be made more apparent as this description proceeds, especially when considered in connection with the accompanying drawings, wherein:

Figure 1 is a fragmentary perspective view of a bending machine embodying my improved power means for actuating the bending fixture;

Figure 2 is a sectional view taken on the line 2—2 of Figure 1;

Figure 3 is a plan view of the bending fixture illustrated in Figure 1;

Figure 4 is a sectional view taken on the line 4—4 of Figure 3;

Figure 5 is a sectional view taken on the line 5—5 of Figure 3;

Figure 6 is a sectional view taken on the line 6—6 of Figure 5;

Figure 7 is a semi-diagrammatic view of the means for connecting the bending fixture shown in Figure 1 to the source of power;

Figure 8 is a fragmentary side elevational view of a slightly modified form of the invention;

Figure 9 is a fragmentary plan view of the construction shown in Figure 8;

Figure 10 is a sectional view taken on the line 10—10 of Figure 8;

Figure 11 is a sectional view taken on the line 11—11 of Figure 8 showing the bending mechanism adapted to be actuated by the power means illustrated in Figure 8;

Figure 12 is a semi-diagrammatic view illustrating the means for operatively connecting the bending fixtures shown in Figure 8 to the source of power.

Although it will be apparent as this description proceeds that the power means may be employed with any one of a number of different types of bending fixtures, nevertheless, for the purpose of illustration and simplification, I have shown my improved power means in association with a bending fixture of the general type featured in the Broomham pending application, Serial No. 682,007, filed at an even date herewith. In detail,

the bending machine comprises a table 15 provided with a substantially flat horizontally disposed top section 16 having a die 17 suitably secured to the upper side of the top section 16. As

shown particularly in Figure 3, the die 17 is curved in the direction of the length thereof corresponding to the degree of curvature it is desired to form in the strip stock or garnish molding designated

herein by the reference character 18. The inner 30 face of the die is uninterrupted throughout its length for the purpose to be presently described, and the outer face of the die is formed with a groove 19 therein throughout the length of the

same having a cross sectional contour corresponding to the cross sectional contour of the strip 18. The particular strip 18 shown herein is substantially channel-shaped in cross section, and, accordingly, the groove 19 is correspondingly shaped. The size of the groove 19 is such as

to freely receive the strip 18 and engage the exterior surface of the latter substantially throughout the area of said surface so that the same will not be deformed upon actuation of the bending shoe 20.

The shoe 20 is slidably mounted upon the table top adjacent the grooved side of the die 17 and is provided with an inwardly extending portion 21 projecting into the groove 19 or, in other words, into the strip 18 so as to engage the inner

surface of the latter as clearly shown in Figure 4. Inasmuch as the entrance end of the die engages one side of the strip 18 and the shoe 20 engages the opposite side of the strip, it will be apparent that movement of the shoe in the direction of

45

50

55

length of the die will compel the strip to assume the curvature of the die. In this connection, it is to be noted that the shoe is guided throughout the aforesaid movement by engagement of the 5 inner face thereof with the outer face of the die, and vertical displacement of the shoe relative to the die is prevented by forming a shoulder 22 at the inner side of the shoe adjacent the upper 10 end thereof for engaging the underside of a projection 23 extending outwardly from the upper end of the die.

Referring now to the mechanism for effecting movement of the shoe 20 in the direction of length of the die 17, it will be noted from Figure 4 that 15 I provide an arm 24 disposed above the die 17 and having the inner end pivotally supported from the table at a point spaced inwardly from the die 17 in such a manner as to permit the arm to swing in a substantially horizontal plane. In 20 detail, the inner end of the arm 24 rests upon a thrust bearing 25 which in turn is seated upon a bearing block 26 fixed to the table top 16, and both the arm and bearing are held in assembled 25 relation with the block by means of a pin 27 having a reduced portion threaded in a tapped opening formed in the block 26. The outer end of the arm 24 is operatively connected to the shoe 20, but in view of the fact that the axis of pivotal 30 movement of the arm is not necessarily the axis about which the die 17 is curved, suitable mechanism must be incorporated to compensate for any variation between the two aforesaid axes. This mechanism comprises a guide member 29 interposed between the lever 24 and die 17 and pivotally connected intermediate the ends thereof to the arm 24 for swinging movement relative to the arm in a plane parallel to the plane of pivotal movement of the latter. The aforesaid pivotal 35 connection comprises a pin 30 slidably mounted in a slot 31 formed in the arm 24 in the direction of length of the latter and having the upper end fixed to a washer 30' slidably engaging the top side of the arm 24 and bridging the slot 31 therethrough to support the pin in the latter slot. The 40 lower end of the pin 30, on the other hand, is threaded for attachment to the guide member 29, with the result that the latter is connected to the arm 24 in such a manner as to permit the same to slide relative to the arm in the direction of 45 length thereof as well as swing relative to said arm. The extreme inner end of the member 29 is provided with a roller 32 for engaging the uninterrupted inner face of the die 17 at a point directly opposite the point of engagement of the 50 shoe with the strip 18 in the die. It will be observed from the foregoing that upon swinging the arm 24 about its axis, the member 29 will follow a path determined by engagement of the roller 32 with the inner surface of the die irrespective of 55 the position of the axis of swinging movement of the arm 24 relative to the axis of curvature of the die due to the substantial universal connection of the member 29 with the arm 24. Consequently, the member 29 may be employed for moving the 60 shoe 20 throughout the length of the die 17, and, in the present instance, the shoe 20 is connected to the member 29 by means of a pair of blocks 33 and 34 slidably mounted in a T-shaped slot 35 formed in the member 29. The slot 35 extends 65 in the direction of the length of the member 29 so as to provide for relative sliding movement of the blocks in a corresponding direction, and the innermost block 34 is provided with an inwardly 70 extending projection 36 engageable in a recess 20' formed in the outer face of the shoe 20 for

moving the shoe relative to the die upon swinging movement of the member 29 by the arm 24. The outermost block 33, on the other hand, is connected to the free end of the member 29 by means of a toggle 37 comprising a pair of pivotally connected links 38 and 39 actuated by a suitable handle 40 connected to the outer end of the link 39. In detail, the connection between the toggle and member 29 is effected by pivotally connecting the link 39 intermediate the ends thereof to the extremity of the member 29 as at 41 and by pivotally connecting the inner end of the link 38 to the outermost block 33 as at 42. In the position of the parts shown in Figure 4, the toggle is in its inoperative position so that straightening 15 of the toggle by swinging the handle 40 downwardly effects an inward sliding movement of the block 33 relative to the member 29 or toward the block 34. In order to impart a like movement to the block 34 and at the same time provide for 20 yieldably urging the projection 36 into operative relation with the shoe, I employ a coil spring 43 having the opposite ends located within counterbored openings formed in the adjacent faces of the blocks 33 and 34. 25

With the parts as thus far described, and assuming that a strip is in operative relation with the die as shown in Figure 3, and that it is desired to bend this strip to conform to the die, the operator manipulates the handle 40 to 30 straighten the toggle 37 and thereby yieldably urges the shoe 20 into frictional engagement with the inner side of the strip to be bent. Upon completion of this operation, the arm 24 is caused to move about the axis of the pivotal connection 35 of the same with the table top, and through the intermediary of the operative connection between the arm and shoe 20, the latter is moved throughout a path defined by the die so as to bend the strip 18 to the contour of the die. After the strip 40 has been bent to the desired contour, the toggle 37 is again broken, releasing the pressure upon the shoe 20 and permitting the finished strip to be removed from the die.

In order to prevent creeping of the strip along 45 the die during the bending operation, it is desirable to provide some means for clamping the strip to the die, and this is accomplished by a clamp designated generally in Figure 1 by the reference character 45. The clamp 45 engages 50 the portion of the strip in the die behind the shoe 20 and comprises a bracket 46 fixedly secured to the table top 16 having laterally spaced ears 47 between which an operating handle 48 is pivotally connected as at 49 intermediate the ends 55 thereof. The extreme inner end of the handle 48 is pivotally connected as at 50 to the outer end of a clamping member 51 having a projection 52 on the inner end thereof extending into the groove 19 of the die for engagement with the strip to be 60 bent. The foregoing construction is such that when the operating handle 48 is in the position thereof shown in Figure 1, the projection 52 exerts a pressure upon the strip for clamping the same in the groove 19 of the die, and when the 65 operating handle 48 is moved downwardly from the position thereof mentioned above, the aforesaid pressure is relieved permitting unobstructed removal of the strip from the die and at the same time permitting the next strip to be assembled 70 with the die by sliding the same endwise into the groove 19.

As hereinbefore stated, the present invention concerns itself more particularly with power means for effecting the necessary swinging move- 75

ment of the arm 24 to cause the desired travel of the shoe 20 throughout the length of the die 17. The power means referred to above comprises a swinging beam 53 fixed at its inner end to a sleeve 54 which in turn is journaled at the lower end within a ring 55 formed on the arm 24 for rotation about the axis of swinging movement of the arm 24. Splined within the sleeve 54 is a drive shaft 56 operatively connected at the upper end to a suitable prime mover (not shown) through the medium of a clutch 57 having coaxially arranged, relatively slidably sections 58 and 59 provided with cooperating interengaging teeth 60. In the present instance, the clutch section 59 is directly connected to the power take-off shaft of the prime mover for rotation therewith as a unit, while the clutch section 58 is splined upon a shaft 56 having a worm 57 thereon meshing with a worm wheel 58' keyed to the shaft 56. The construction is such as to provide for movement of the clutch section 58 into and out of mesh with the section 59 to connect and disconnect the drive shaft from the source of power.

25 In order to actuate the splined clutch section 58 in timed relation to the actuation of the bending fixture, the section 58 is operatively connected to a reciprocable bar 61 normally urged in a direction to move the section 58 into mesh with the section 59 by means of a spring 62. The operation of the spring 62 to move the bar 61 and the movement of the latter to disengage the clutch is automatically controlled in timed relation to the operation of the bending fixture through the medium of the mechanism designated generally herein by the reference character 63.

The mechanism 63 comprises a disk 64 keyed to the drive shaft 56 and connected to the bar 61 by means of a lever 65 having the inner end journaled upon the drive shaft 56 directly above the disk, and having the free end projecting beyond the periphery of the disk for connection with the bar 61 by the rod 66. Mounted upon the underside of the disk 64 is a pawl 67 pivotally connected intermediate the ends thereof to the disk for swinging movement about a substantially horizontal axis designated herein by the reference character 68 and having the outer end extending beyond the periphery of the disk. The latter end of the pawl is provided with an upwardly extending projection 69 normally urged to a position above the disk for engagement with the lever 65 by means of a spring 70 interposed between the disk and inner end of the pawl. The pawl is operated against the action of the spring 70 to move the projection 69 out of the plane of the lever 65 by means of a flexible member 71 having the upper end operatively connected to the inner end of the pawl and having the lower end fixed to a sleeve 72 rotatably mounted upon the drive shaft 56. The construction is such that rotation of the sleeve 72 in the direction of the arrow 73 effects a pivotal movement of the pawl 67 about its axis 68 to withdraw the projection 69 on the pawl out of the plane of the lever 65. Rotative movement of the sleeve in the direction of the arrow 73 to effect the foregoing results is accomplished herein by means of a flexible member 74 having the inner end connected to the sleeve and having the outer end connected to a suitable operator 75 provided with a handle 76 positioned for convenient manipulation by the operator.

75 The pawl 67 and lever 65 are so located with

reference to the bending fixture that in the initial position of the latter, the pawl holds the arm in its inoperative position against the action of the spring 62 through the medium of the connection of the lever 65 with the arm or, in other words, holds the clutch in its disengaged position. As soon as the operating handle 40 is manipulated to clamp the strip of metal to be bent in the die by the shoe 20, the projection 69 of the pawl is withdrawn from engagement with the lever permitting the spring 62 to move the arm 61 in a direction to engage the clutch and thereby effecting a rotation of the drive shaft. Inasmuch as it is essential to manipulate the handle 40 to clamp the shoe in place prior to releasing the pawl, both of the latter functions may be accomplished by one operation rendering it unnecessary to manipulate the handle 76. As shown in Figure 4, the handle 76 is provided with a downwardly extending projection 80 positioned in advance of an upwardly extending projection 81 located on the handle 40 at a point spaced outwardly from the pivotal connection of the link 39 with the member 29 so that downward movement of the handle 40 to straighten the toggle will effect a rearward movement of the operator 75 to withdraw the pawl in the manner previously set forth. In this connection, it is to be noted that the position of the projection 80 relative to the projection 81 may be accurately varied to insure movement of the operator 75 upon actuation of the handle 40 by means of an adjusting screw 82 normally held in engagement with the free end of the beam 53 by means of a spring 83.

Thus, from the foregoing, it will be observed that as soon as the toggle 37 is straightened, the projection 69 is disengaged from the lever 65 permitting movement of the arm 61 by the spring 62 to engage the clutch, and thereby effect a rotation of the drive shaft 56. Incidentally, movement of the arm 61 to engage the clutch effects a corresponding movement of the lever 65 in a direction opposite to the direction of rotation of the disk 64 or drive shaft 56 so that the projection 69 will again engage the lever 65 before the drive shaft has completed one revolution, but in view of the fact that the clutch remains in engagement until the arm 61 is retracted the same distance that it is advanced to engage the clutch, it will be apparent that actual disengagement of the power will not take place until the lever 65 is returned by the pawl 67 to the original position thereof shown in Figure 1 or, in other words, until the drive shaft is rotated one complete revolution.

In the present instance, the shoe 20 is moved throughout the length of the die 17 by a connection between the beam 53 and arm 24. However, in view of the fact that the beam 53 is connected to the drive shaft 56 through the medium of the sleeve 54 for rotation as a unit with the drive shaft, the operative connection between the beam and arm 24 is such as to release the latter from the former when the curvature in the metal has been completed so as to permit the beam to complete its revolution with the drive shaft 56. The aforesaid connection comprises a bracket 85 secured to the beam intermediate the ends thereof and having laterally spaced ears 86 forming a pivotal support for the upper end of a finger 87 having the lower end projecting downwardly below the beam 53 for engagement with the arm 24 at a point spaced from the pivotal connection of the arm with the table so as to

push the arm around the aforesaid pivotal connection. Although a suitable spring pressed plunger 88 is carried by the bracket for engaging a portion 89 of the finger extending above the 5 pivotal connection with the bracket tending to maintain the lower end into engagement with the arm 24, nevertheless, this means in itself is not sufficient to overcome the reaction of the arm in moving the shoe throughout the length of the die, 10 and for accomplishing this result, I provide means for positively locking the finger in its operative position relative to the arm 24. This latter means is shown in Figure 6 as comprising a pair of jaws 90 disposed beneath the beam 53 upon opposite 15 sides of the bracket 85 and finger 87. The jaws are pivotally connected to the bracket 85 through the medium of pivots 91 for swinging movement toward and away from opposite sides of the finger 87, and the free ends of the jaws are normally 20 yieldably maintained into engagement with the latter sides of the finger by means of a spring 92 acting upon the pivoted ends of the jaws beyond the pivots 91. The free ends of the jaws, on the other hand, are provided with enlarged portions 25 93 forming shoulders 93' for engagement with the front side of the swinging end of the finger to maintain the same against the corresponding side of the arm 24, and this action is insured herein by means of a latch member 94 having an opening 95 therethrough for receiving the free ends of 30 the jaws and pivotally connected as at 96 to one of the jaws. The construction is such that when the latch member has been swung to the position thereof illustrated in Figure 6 wherein the free 35 ends of both jaws extend into the opening 95 in the latch member, the jaws are positively locked with the shoulders 93' in engagement with the swinging end of the finger, and accidental swinging movement of the latch member to release the jaws is prevented by means of a spring 97 located 40 in the manner clearly illustrated in Figure 6. The free end of the latch member extends laterally beyond the bracket to such an extent as to engage a trip 98 upon completion of the bending 45 operation. The trip 98 is, of course, fixed relative to the latch member so that as the beam passes the trip, the same will swing the latch member about its pivotal connection 96 against the action of the spring 97 to unlock the jaws 50 from engagement with the free end of the finger 87. After the latch has been disengaged in the manner specified above, the relatively light spring 92 is insufficient to counteract the resistance to continued rotation of the bending fixture by the beam 53, with the result that the free ends of 55 the jaws will be forced to swing outwardly by the swinging end of the finger as the latter passes over the arm 24. The bending fixture may then be manually returned to its original starting position, while the beam 53 completes its revolution. 60

If desired, the beam may be employed to automatically release the clamp 45 during the interval of movement of the same from the trip 98 to its initial starting position, and this is accomplished herein by a lever 99 pivotally connected intermediate the ends thereof as at 100 to the side of the table top in such a manner that the upper end assumes a position in the path of travel of the beam to be engaged by the latter. The lower 65 end of the lever, on the other hand, is connected by a flexible member 101 to the free end of the handle 48 so that as the beam swings the lever 99 in the direction of the arrow 102, the free end of the handle will be lowered through the medium 70 of the flexible member 101 to release the clamp. 75

After the beam is returned to its initial position in the manner outlined above, the free end of the finger 87 is merely forced between the enlarged end portions of the jaws to the position thereof shown in Figure 6 whereupon the apparatus is ready for the next bending operation. 5

In some cases, it may be desirable to form two curves in a strip of metal, and in order to accomplish this result expediently, I provide the apparatus shown in Figures 7 to 11, inclusive. In accordance with the present embodiment, both curvatures in the strip are formed simultaneously by a pair of bending fixtures 102' and 103 identical to the bending fixture hereinbefore set forth in so far as the construction thereof is concerned. 10 In the present instance, both the aforesaid bending fixtures cooperate with a common die 17' differing from the die 17 in that the opposite ends are curved to correspond to the curvature it is desired to form in the strip designated in Figure 15 20 11 by the reference character 18'. The strip 18' is clamped to the die 17' intermediate the bending fixtures by means of a clamp 45' identical in construction and operation to the clamp 45 previously described. With the construction as briefly 25 set forth above, it will be apparent that after the straight strip 18' has been inserted between the die and shoes associated with the bending fixtures and the clamp 45' has been manipulated to secure the strip in place, both of the bending fixtures are swung simultaneously in directions away from each other around the curved end portions of the die to bend the strip to the contour of the die. Inasmuch as the construction of both the bending fixtures 102' and 103 is identical to the 30 35 construction of the bending fixture hereinbefore described, it necessarily follows that the former operate in the same manner as the latter to bend the strip around the die. However, in the present instance, the swinging beams 53' of both the bending fixtures 102' and 103 are not rotated one complete revolution as in the first described form of the invention, but, on the other hand, are arrested soon after the bending operation is completed as will be more fully hereinafter described. 45

In the present embodiment of the invention as in the first described form thereof, the bending shoe actuating arms 24' are operatively connected to the beams 53' by the same mechanism set forth above. In the present instance, however, the beams 53' are swung a sufficient distance only to release the fingers 87' from the arms 24' by the stops 98' or, in other words, the beams 53' are arrested before the fingers 87' actually pass over the arms 24'. By restricting relative movement 50 of the beams and arms to such an extent as to prevent passing of the fingers 87' over the arms, the fingers will be maintained on the same sides of the arms 24' at all times. By providing the aforesaid means for releasing the arms 24' from the beams 53', accurate bending of the strips of metal is insured, since the arms are arrested at a predetermined point irrespective of any slight over travel of the beams 53'. In addition, it is 55 to be noted that each of the trips 98' may be adjusted to vary the positions thereof relative to the latch members 94' and thereby provide for varying the degree of curvature of the bend in the strip. 60

Referring now more in detail to the mechanism 70 for simultaneously actuating the bending fixtures 102' and 103, it will be noted that both of the latter are provided with drive shafts 104 and 105 respectively connected to the swinging beams 53' of the fixtures in the same manner as the drive 75

shaft 56 is connected to the swinging beam 53 of the bending fixture in the first described form of the invention. In the present instance, the drive shaft 105 is operatively connected to the drive shaft 104 through the medium of a gear train 106 for rocking the shaft 105 in a direction opposite to the direction of rocking movement of the shaft 104. The gear train 106 comprises a pair of gears 107 and 108 respectively secured to the upper ends of the drive shafts 104 and 105 and operatively connected by a pair of intermeshing pinions 109. As shown particularly in Figure 9, the intermeshing pinions 109 respectively mesh with the gear wheels 107 and 108 at points spaced from the points of intersection of a line 110 passing through the axes of both drive shafts so as to permit varying the distance between the latter axes without the necessity of interchanging any part of the gear train 106. As a matter of fact, the gear train is so supported as to provide for varying the distance between the axes of the two drive shafts without disconnecting the gear train therefrom, and this is accomplished herein by mounting the pinions 109 upon a common bracket 111 having the opposite ends respectively pivotally connected to the drive shafts 104 and 105 by links 112.

The shaft 104 is operatively connected to a countershaft 113 having a pair of pulleys 114 and 115 freely rotatably mounted thereon in axial spaced relationship. Both pulleys are operatively connected to a power shaft (not shown) through the medium of suitable belts 116, and the belt for the pulley 115 is preferably twisted so that this latter pulley will rotate in a direction opposite to the direction of rotation of the pulley 114. The pulleys are selectively secured to the countershaft for rotation therewith as a unit by means of a clutch 117 splined upon the shaft and having clutch teeth 118 and 119 upon opposite ends for respectively engaging cooperating teeth upon the pulleys 114 and 115 upon movement of the clutch in opposite directions relative to the shaft 113. The clutch is moved axially of the shaft by means of an arm 120 pivotally supported intermediate the ends as at 120' and having a fork at the upper end for engagement in an annular groove 121 formed in the clutch 117. The lower end of the arm, on the other hand, is connected to an operating bar 122 extending in a direction transverse to the arm 120 and having a handle portion 122' conveniently located for manipulation by the operator.

Assuming that the clutch 117 is in its neutral position between the aforesaid pulleys and that the operating bar is moved in the direction of the arrow 123, it will be noted that the clutch will be moved axially of the countershaft 113 in an opposite direction to secure the pulley 114 to the countershaft 113, and thereby connect both the drive shafts 104 and 105 to the source of power. On the other hand, movement of the bar in the opposite direction or in the direction of the arrow 124 effects a movement of the clutch 117 into engagement with the pulley 115 to rotate the countershaft as well as both of the drive shafts in directions opposite to the directions of rotation thereof by the pulley 114. It will, of course, be understood that the drive shaft 105 will always be rotated in a direction opposite to the direction of rotation of the drive shaft 104 irrespective of which of the pulleys is secured to the countershaft 113.

As shown particularly in Figure 8, the operating bar 122 is yieldably connected to a fixed sup-

port 125 by means of a spring 126 in such a manner that movement of the bar in the direction of the arrow 123 or, in other words, in a direction to connect the pulley 114 to the countershaft, places the spring under tension tending to move the bar in the direction of the arrow 124 to disengage the clutch 117 from the pulley 114 and to engage the clutch with the pulley 115. In this connection, it is to be noted that the strength of the spring is not sufficient to counteract the torque on the clutch teeth and disengage the clutch from the pulley 114, but is sufficient to engage the clutch with the pulley 115 after the clutch has been positively disengaged from the pulley 114. The manner in which the positive disengagement is effected will be more fully hereinafter set forth. Accidental movement of the bar by the spring 126 is prevented herein by means of a catch 127 comprising a latch member 128 having a shoulder 129 for engagement with a dog 130 fixed to the bar 122 at a point so determined that when the clutch 117 is in mesh with the pulley 114, the dog engages behind the shoulder 129. The latch 128 is fixed relative to the dog upon the support 125 and is connected to the latter by means of a leaf spring 131 stronger than the spring 126, but sufficiently flexible to provide for disengagement of the dog from the latch upon positively moving the bar 122 in the direction of the arrow 124.

As pointed out above, the bending fixtures or the swinging beams 53' of the latter are moved through a predetermined arc as distinguished from the beam 53 in the first described form of the invention which is rotated one complete revolution. In order to control the rocking movement of the beams 53' by the drive shafts 104 and 105, I provide the mechanism designated generally herein by the reference character 132. This mechanism comprises a disk 133 fixed upon the drive shaft 104 and having a pair of circumferentially spaced stops 134 and 135 adjustably secured to the periphery thereof. These stops are provided with portions projecting above the plane of the disk for engagement with an arm 136 having the inner end swivelly mounted upon the drive shaft 104 and having the outer end connected to the operating bar 122 by means of a link 137. Both the stops 134 and 135 are accurately located upon the disk with reference to the arm 136 so that when the clutch 117 is in its neutral position or, in other words, when the arm is in its normal position shown in Figure 10, the distances 138 and 139 between the respective stops and arm 136 correspond to the desired arcuate travel of the beams 53'.

The foregoing construction is such that when the bar 122 is moved in the direction of the arrow 123 to engage the clutch 117 with the pulley 114, the arm 136 is moved a corresponding distance opposite to the direction of rotation of the disk 133 effected by the pulley 114 or, in other words, toward the stop 135. As soon as the clutch 117 is in mesh with the pulley 114, the disk and associated parts including the bending fixtures are rotated in the direction of the arrow 140 until the stop 135 engages the arm 136 and moves the latter to its normal position shown in Figure 10 to disengage the clutch from the pulley 114. As soon as the clutch is disengaged from the pulley 114, the spring 126 automatically moves the bar in the direction of the arrow 124 to engage the clutch 117 with the pulley 115, and owing to the connection of the arm 136 with the bar, the former will be moved in a direction toward the stop 134. Engagement of the clutch 117 with the pulley 115

effects a movement of the disk in the direction of the arrow 141 until the stop 134 engages the arm 136 and moves the same back to its normal position wherein the power to the beams 53' will be disconnected. The arrangement is such that the extent of movement of the arm in the direction of the arrow 140 is identical to the extent of movement of the arm in the reverse direction 141 so that the beams will be returned to their original starting positions upon completion of each bending operation. Inasmuch as the arms 24' or the bending fixtures proper are released from the beams in the manner stated above just prior to arresting the latter, these arms and associated parts are returned to their initial starting positions manually. In this connection, it is to be noted that in the latter embodiment of the invention as in the first described modification, the adjacent surfaces of the free ends of the clamping jaws 90 are chamfered as shown in Figure 6 so as to facilitate movement of the free ends of the fingers carried by the swinging beams. The fingers are preferably engaged with the clamping jaws prior to returning the arms 24' to their initial starting positions so that these fingers will act as stops to limit the return movements of the arms and thereby accurately position the latter in readiness for the next bending operation.

Thus, from the foregoing, it will be observed that the present invention provides power means for operating either one or a plurality of bending fixtures simultaneously, and, in addition, insures accurate bending of the stock by employing means for accurately controlling the operation of the power mechanism as well as means for releasing the bending fixture from the power mechanism independent of the aforesaid means. It will also be observed that in the first described embodiment, the degree of curvature may be varied by accurately adjusting the trip 98 relative to the finger 87, and in the second modification, by adjusting both the trips 98' and stops 134 and 135 relative to the lever 136. It will further be apparent that the principle involved is relatively simple, and while particular stress has been placed upon the details of construction of both embodiments of the invention, reservation is made to make such changes in these details as may come within the purview of the accompanying claims.

50 What I claim as my invention is:

1. In a bending machine, the combination with a bending fixture movable throughout a predetermined path of travel, of a member mounted for rotation relative to said fixture, means connecting the fixture to said member, power means operatively connected to said member for imparting a rotative movement thereto, means automatically operable to disconnect the power means from the member after a predetermined interval of operation of the latter, and means operable independent of the said last named means to arrest movement of said fixture.

2. In a bending machine, the combination with a bending fixture movable throughout a predetermined path of travel, of a member mounted for rotation relative to said fixture, means connecting the fixture to said member, power means operatively connected to said member for imparting a rotative movement thereto, means for automatically arresting said member after one complete revolution of the latter, and means for arresting said fixture after a predetermined interval of rotative movement of said member.

3. In a bending machine, the combination with a bending fixture movable throughout a predeter-

mined path of travel, of a member mounted for rotation relative to said fixture in a plane substantially parallel to the plane of movement of the latter, power means for imparting a rotative movement to said member, means connecting the member to the fixture, means for disconnecting the fixture from said member after a predetermined interval of operation of the fixture, and means for varying the interval of operation of said last named means to vary the distance of travel of the fixture.

4. In a bending machine, the combination with a bending fixture movable throughout a predetermined path of travel, of a rotatable member operatively connected to the fixture, power means for imparting a rotative movement to said member, means for arresting said member after a predetermined extent of travel thereof, and means operable independent of said last named means for disconnecting the fixture from the member at a predetermined point in the path of travel of the latter.

5. In a bending machine, the combination with a bending fixture movable throughout a predetermined path of travel and a clamp for securing a strip of metal to be bent in operative relation to said fixture, of a power actuated member movable relative to the fixture, means connecting the fixture to said member, means for releasing the aforesaid means at a predetermined point in the path of travel of said member, and means operated by the member upon continued movement of the latter to release said clamp from the bent strip of metal.

6. In a bending machine, the combination with a plurality of bending fixtures movable throughout predetermined paths of travel, of a plurality of members corresponding in number to the number of bending fixtures and respectively connected to the latter, power means for actuating said members, and means for releasing the fixtures from said members at predetermined points in the path of travel of the latter.

7. In a bending machine, the combination with a plurality of bending fixtures movable throughout predetermined paths of travel, of a plurality of members corresponding in number to the number of bending fixtures and respectively connected to the latter, power means for actuating said members simultaneously, and means associated with each fixture for independently releasing each fixture from its driving member at predetermined points in the paths of travel of said members.

8. In a bending machine, the combination with a plurality of bending fixtures movable throughout predetermined paths of travel, of a plurality of members corresponding in number to the number of bending fixtures and respectively connected to the latter, power means for actuating said members simultaneously, means associated with each fixture for independently releasing each fixture from its driving member at predetermined points in the paths of travel of said members, and means for independently varying the interval of operation of the said last named means to vary the distances of travel of the fixtures.

9. In a bending machine, the combination with a plurality of bending fixtures movable throughout predetermined paths of travel, of a plurality of members corresponding in number to the number of bending fixtures and respectively connected to the latter, power means for actuating said members simultaneously, means for re-

leasing the members from the power means, and means operable independent of said releasing means to arrest movement of the fixtures.

10. In a bending machine, the combination with a plurality of bending fixtures movable throughout predetermined paths of travel, of a plurality of members corresponding in number to the number of bending fixtures and respectively releasably connected to the latter, power means

for actuating said members simultaneously, means operable in dependence upon a predetermined interval of movement of said members for automatically disconnecting the power means from said members, and means operable independent of said last named means for automatically releasing the fixtures from said members.
